**METHOD FOR THE CONTROLLED FEEDING
OF MATERIAL TO PROCESSING UNITS**

Wilhelm Walter Karl Quester, Cologne, Germany,
assignor to Wilh. Quester, Cologne-Sulz, Germany, a
firm

Filed Dec. 8, 1959, Ser. No. 858,277

Claims priority, application Germany Dec. 10, 1958
2 Claims. (Cl. 214—152)

This invention relates to a method and an apparatus for continuously feeding material to a plurality of processing or fabricating means at a rate which is dependent upon the consumption, and more particularly to a method and apparatus for fully automatically feeding cut tobacco to any number of cigarette making machines.

Many attempts were made in the past to solve the problem of automatically feeding cigarette making machines with cut tobacco. As a result of these attempts, mechanically operating apparatus was developed which, in dependence upon the consumption of each single machine, automatically fed the tobacco in portions.

In case of pneumatically operating feeders, it was usual to use semi-automatic systems with the feeding of tobacco to the pneumatic units being effected and controlled manually. In pursuing the efforts to mechanize the feeding of tobacco, various methods and devices were suggested and tried, of which the rotary feeding disc provides a maximum of careful treatment of the tobacco in distributing the same.

If only one disc is provided, the stream of tobacco coming from the cut tobacco stock bin can be adjusted to the particular quantity required. However, the simultaneous feeding of several discs from a common stock bin necessitates a consumption-controlled distribution system since the number of machines to be fed may vary within short periods of time at any disc, e.g. by machine breakdown, replacement of paper, and the like.

The object of this invention is a further improvement of a method and an apparatus which permit a consumption-controlled distribution to any number of consumer units. It is characterized in that the material is passed in succession to several processing or fabricating units at the rate per unit time required for continuous feeding, but with the sizes of portions corresponding to the feeding cycle, the feeding being effected in the time intervals predetermined for said units. In case of incomplete acceptance of the material, the same is passed to accumulator means during the residual time remaining for the respective unit. While traveling from the point of delivery from the continuous feed stream to the processing or fabricating unit, the allocated sizes of portions are converted into a continuous delivery stream of material, it being possible for the supply of the material to be effected either from the stock bins or from the accumulator means.

In accordance with the invention, the conveying means leading to the processing or fabricating units arranged in series one after the other comprises successive conveyor belts between which, at the distribution points for the material to the units, intermediary members are interposed which may be adjusted as bridging members between the conveyor belts and for distribution of material to the individual consumer units. The intermediary members are preferably designed as flap valves which, in one position, pass the material from the higher end of the preceding conveyor belt to the lower receiving end of the following conveyor belt or, in the other position, to the processing or fabricating unit.

It is achieved by means of the method and the apparatus of the invention that so much tobacco is continu-

2

ously fed to the processing or fabricating units as corresponds to the actual consumption of the processing or fabricating units which are in operation at any one time. The distribution of the total quantity is not effected by subdividing the same into parallel streams, but only by portions delivered at a time sequence. The supply of these portions is effected at such time intervals that a partial stream without intervals is formed which corresponds to the current requirement of the individual consumer units. The requirement of the consumer units may undergo a constant variation due to failure or other troubles. The process of the invention is adapted to these fluctuations. The quantity of material effectively supplied to the processing units corresponds at any one time to the quantity actually required, i.e. consumed. The delivery of excess quantities is avoided.

The process of the invention is preferably accomplished by the apparatus shown in the accompanying drawings, wherein,

FIG. 1 is a side elevational view of the overall unit;
FIG. 2 is a top plan view of the unit shown in FIG. 1, and

FIG. 3 is a vertical sectional view on an enlarged scale taken on line 3—3 of FIG. 1.

The apparatus for carrying out the process comprises a supply means which, in the present case, is in the form of three bins 1, 2 and 3 having the bottoms constructed as conveyor belts that communicate with the conveyor belts 4, 5 and 6 which lead to a delivery device consisting of a plurality of conveyor belts 7, 8, 9 and 10 arranged one after the other in the direction of movement. Between these individual conveyor belts 8, 9 and 10 are provided flap valves 11, 12, 13 and as shown in FIGS. 1 and 3. These flap valves, when in one position, bridge the distance between the adjacent conveyor belts. In the other position of the flap valves, the material is permitted to drop onto the conveyor belts 14, 15 and 16 leading to the consumer units which, in the present embodiment, are represented as the feed discs 17, 18 and 19. In order that the material be supplied in uniform thickness to the conveyor belts 14, 15 and 16, a swing funnel 20 shown in detail in FIG. 3 and pivotally mounted as at 20a, may be provided in each space below the flap valves 11, 12, 13, said funnel being constantly moved to and fro while the material is deposited on the conveyor belts 14, 15 and 16. The last conveyor belt of the feeding unit, e.g. the belt 10, is followed by a further conveyor belt 21 which may be supplemented by a further conveyor belt 22 which returns the material to one of the first conveyor belts 4, 5 or 6. In the present case, the return of material is effected to the conveyor belt 6. The conveyor belts 21, 22, etc. used for returning excess quantities simultaneously represent accumulator means for any excess quantities which are not accepted at the points of delivery, i.e. the receiving belts 14, 15, 16. Character 23 is a photocell which controls the level of the accumulator belt 22 temporarily receiving excess quantities.

The embodiment shown relates to the feeding of cut tobacco to cigarette making machines, but may also be used in other fields. The apparatus in accordance with the invention is designed in such a way that the quantity of cut tobacco exactly corresponding to the actual consumption is fed at any one time to each of the feeding discs 17, 18, 19. This means that the quantity withdrawn from the supply bins 1, 2, 3 must correspond to the maximum possible quantity in order to be able to meet any requirement encountered.

Normally, an excess quantity will have to be expected which is not accepted by the feeding discs. This excess quantity has to be kept in store for renewed delivery or to be returned into the supply unit. The supply unit 1,

2, 3, in the present embodiment, is designed in such a way that it is either filled or discharged. Simultaneous filling and discharge is not provided. For this reason, the excess quantities, in accordance with the invention, are passed to an independent intermediate storage unit and returned into the process cycle at a suitable time.

With such an arrangement, the following partial problems have to be solved.

(a) Formation of tobacco portions in relation to the actual consumption of the consumer unit, i.e. the feeding disc.

(b) Converting the portions into continuous tobacco streams for uninterrupted feeding to the discs.

(c) Intermediate storage of the excess quantities.

Regarding the feature (a), i.e. formation of portions, the assumption is made that each of the cigarette making machines, while in operation, requires a constant quantity of cut tobacco per minute. Thus, it is only necessary to determine for each of the feeding discs the number of running machines in proportion to the total number of machines connected. A counter equipped with a relay combination exactly furnishes this value.

Example

Table 17—6 machines

Table 18—6 machines

Table 19—6 machines

Installed is a total of 18 machines

Running on table 17 are 4 machines

On table 18—6 machines

On table 19—5 machines

Presently running is a total of 15 machines

Thus, for example, the fraction of the total quantity of tobacco to be delivered in 1 minute would be

$\frac{4}{18}$ to table 17

$\frac{6}{18}$ to table 18

$\frac{5}{18}$ to table 19

while $\frac{3}{18}$ would have to be stored in the intermediate storage.

It may be assumed for this example that the delivery cycle is 1 minute=60 seconds, i.e. that after expiration of this cycle the delivery of the portion will start again with table 17.

Thus, with all of the 18 machines in full operation tobacco would be supplied,

To table 17 from the 1st to the 20th second,

To table 18 from the 21st to the 40th second,

To table 19 from the 41st to the 60th second,

and again

To table 17 from the 61st to the 80th second,

To table 18 from the 81st to the 100th second,

To table 19 from the 101st to the 120th second,

and so on.

However, since some of the machines are not running, tobacco is delivered

To table 17 (4 machines) from the 1st to the 13th second,

To table 18 (6 machines) from the 21st to the 40th second,

To table 19 (5 machines) from the 41st to the 57th second,

and the excess quantities are stored in the 14th to 20th second and 58th to 60th second.

With this method of time-controlled feeding, i.e. consumption controlled feeding proportional to the number of machines running, the quantity of tobacco corresponding exactly to the consumed quantity is delivered to each of the tables.

Regarding the transformation of the portions into continuous streams in accordance with partial problem (b) the portions formed in dependence upon the consumption by the method described above are to be supplied to

the feed discs continuously. The solution to the problem provides an intermediary conveyor belt 14, 15 or 16 effecting said transformation.

The quantities of tobacco delivered by the supply belts 5, 7, 8 and 9 via a reversing flap valve 11, 12 or 13 are uniformly distributed on an intermediary conveyor belt 14, 15 or 16 by a swing funnel 20. The feed velocity of the intermediary belt is constant. Thus, the thickness of the formed layer is directly proportional to the duration of delivery since the length and width of layer remain constant (provided that the delivered quantity is constant). The deposition on the feed disc is continuous. Since the layer depth corresponds to the duration of delivery and the latter is dependent upon the number 10 of consuming machines, the supply of tobacco always corresponds exactly to the quantity being consumed.

Regarding the intermediate storage of the excess quantities in accordance with partial problem (c), it is to be expected in practice that excess quantities which are necessary in view of a supply ensured in any case, must be stored.

The storage belts 21, 22 provided for receiving these quantities are uniformly filled with the excess partial quantities until their capacity is exhausted. They then 25 interrupt the further supply from the containers 1, 2, 3 and, at the same moment, start to supply the feed discs until their contents is consumed. They then switch back to the supply containers 1, 2, 3 and the cycle starts again.

The apparatus as a whole operates as follows:

30 The tobaccos are passed from the supply containers 1, 2 or 3 to the conveyor belts 4, 5, 6 and then to the conveyor belt 7. The flap valves 11, 12 and 13 are in idle position so that the further travel of the tobacco over the conveyor belts 8, 9, 10 and to the storage 21, 22 is free. All of the belts 8, 9, 10 and 21 are uniformly 35 filled with tobacco. The conveyor belt 22, normally empty, acting as the storage belt is ready to receive tobacco.

The feeding cycle starts with flap valve 11 swinging 40 back, i.e. to the left in the drawing plane i.e. FIG. 1, thereby depositing tobacco on the intermediary conveyor belt 14. The conveyor belts 8, 9, 10, and 21 stop while being laden with tobacco. The storage 22 likewise is idle. Upon expiration of the feed time, the flap valve 11 swings back into the initial position and the conveyor belts 8, 9, 10, and 21 start running. If the flap valve 11 is reversed before the expiration of the maximum possible time, the tobacco is first stored in the storage belt 22. If the maximum was reached, and with the flap valve 11 moving back, the next flap valve 12 is turned into the position permitting the disc 18 to be fed, and the conveyor belts 9, 10, and 21 stop running until the flap valve 50 12 is returned into its initial position. The same sequence of events occurs with the following flap valve 13. Upon completion of the overall cycle, it is started again with the first flap valve 11 and the feed disc 17 and so on.

Thus, tobacco is only passed into the storage unit 22 if, due to non-utilization of the maximum feed period 60 provided for a feed disc, there are existing excess quantities which cannot be immediately passed to one of the consumer units 17, 18, 19, etc. If the storage unit 22 is filled, which is supervised by a photocell 23 or the like, which also transmits the signal for its discharge, the supply bins 1, 2, 3 and the conveyor belts 4, 5 are stopped. The storage belt 22 together with the belts 6 and 7 starts supplying tobacco to the consumer units 17, 18, 19.

With tobacco being supplied from the storage belt 22, 70 which suddenly stops delivering tobacco as its movement stops, which is in contrast to the delivery from the supply bins 1, 2, 3, only that quantity is delivered which is consumed by the consumer units 17, 18, 19 so that a repeated storage of excess quantities is eliminated. The 75 result hereof is that the conveyor belts stop moving in

the initial position of the flap valve and run only in operating position. If the storage belt 22 is empty, the advance movement on this belt ceases. Instead of this, the conveyance from the supply bins 1, 2, 3 and the movement of the belts 4, 5 is started again so that the normal cycle takes place again.

By stopping the belts 8, 9, 10, 21 and 22 while feeding the preceding consumer unit 17 with tobacco withdrawn from the supply bins 1, 2, 3, or by stopping the belts 4, 5, and 8, 9, 10, and 21 when delivering tobacco from the storage belt 22, it is achieved that the stream of tobacco on these conveyor belts is not interrupted and the full quantity is offered at any time if required by the consumer units 17, 18, and 19.

The tobacco will be removed from the tray 17 by the suction device 24 to processing or fabricating means especially cigarette making machines.

What is claimed is:

1. A method for the controlled continuous feeding of bulk material to a plurality of material processing units comprising the steps of continuously supplying bulk material from a bulk material source at a rate at least equal to the combined maximum requirements of the plurality of material processing units over a given period of time determined by the maximum consumption of said processing units, delivering bulk material intermittently and sequentially and in a constant direction to the material

5 processing units in relation to the actual demand requirements of the material processing units during said given period of time continuously accumulating excess material not accepted by said material processing units during the given period of time and making it available to said material processing units during a subsequent time interval and uniformly directing an accumulated supply of excess material during said subsequent time interval to said processing units prior to and independently of supplying said processing units from said bulk source.

10 2. The method of claim 1; including the step of directing said bulk material source in series with the recycled excess material, and directing the supply of material to said plurality of processing units in respectively 15 parallel paths from said supply of material.
